UNITED STATES PATENT OFFICE.

ALEXANDER M. MOYLAN, OF CENTURY, FLORIDA.

TIE AND RAIL-FASTENER.

941,937.

Specification of Letters Patent. Patented Nov. 30, 1909.

Application filed March 23, 1909. Serial No. 485,202.

To all whom it may concern:

Be it known that I, ALEXANDER M. MOYLAN, citizen of the United States, residing at Century, in the county of Escambia and

5 State of Florida, have invented certain new and useful Improvements in Tie and Rail-Fasteners, of which the following is a specification.

This invention relates to railways and has 10 particular reference to an improved tie for supporting the rails of the same.

An object of this invention is to provide a tie which is formed of metal and which possesses the necessary resilient qualities which 15 are produced by the common wood ties now employed and to overcome the main difficulty which has been encountered in the formation of metallic ties.

The invention has for another object the 20 construction of a metallic tie which is provided with clamping means for engaging the bases of the rails which bind tightly upon the rails upon the disposition of weights upon the rails at their clamped points, the 25 clamping means being actuated by the depression of the upper face of the tie in forming a resilient or cushioning supporting means for the rail and thereby binding the same upon such depression.

30 The invention further contemplates the provision of a tie which is provided with means whereby the same may be rigidly anchored beneath the rails in the gravel, sand or the like upon which the ties are 35 positioned and which will prevent the lateral displacement of the same incident to the vibrations caused by the passing of trains over the same.

The invention has for a still further object 40 the provision of a metallic tie which possesses the above enumerated advantages and which at the same time is of simple formation so as to produce a tie which can be economically constructed and thereby brought 45 into general use.

Other objects and advantages derived 50 from the peculiar construction, formations and arrangements of the parts of the invention will be disclosed in the following specification and appended claim.

For a full understanding of the invention reference is to be had to the following description and accompanying drawings, in which:—

Figure 1 is a perspective view of the improved tie disclosing a rail as secured at one end of the same. Fig. 2 is a longitudinal vertical section through the same disclosing two rails engaged with the tie. Fig. 3 is a longitudinal section showing the modified form of rest employed. Fig. 4 is a perspective view of a modified form of a tie in an inverted position. Fig. 5 is a detailed perspective of the rest employed in the preferred form. Fig. 6 is a detailed perspective of the rest employed in the modified form, and Fig. 7 is a detailed perspective of one of the clamps employed in connection with the tie.

Corresponding and like parts are referred 70 to in the following description and indicated in all the views of the drawings by the same reference characters.

Referring to the drawings the numeral 10 designates an elongated plate which is of 75 substantially rectangular formation and which forms the body portion of the tie. The plate 10 is adapted for disposition beneath the rails 11 and 12 and is adapted to support and to be secured to the same. The 80 plate 10 is provided with a depending flange 13 which is disposed about the edges of the same and which is utilized for the purpose of reinforcing the plate 10 and also for holding a body of earth, gravel or the like beneath the tie in order to form a substantial support for the same. The ends of the plate 10 are provided with guards 14 which 85 comprise metallic strips bent into semicircular formation, the opposite ends of the 90 same being clamped in any suitable manner to the flanges 13 at the opposite sides of the plate 10. The guards 14 are each provided with enlarged portions at their opposite ends in order to form a seating member to engage 95 in the earth and to prevent of the falling of the same from beneath the plate 10 when positioned upon embankments or the like. The plate 10 is further anchored in the earth 100 upon which the same is supported by the

provision of a plurality of tongues 15 which are stamped from the plate and bent downwardly to engage in the soil.

The manner of securing the rails 11 and 12 upon the upper face of the plate 10 comprises the formation of slots 16 longitudinally in the opposite ends of the plate 10 to be positioned beneath the bases of the rails 10 and 11 and through which are inserted 10 clamps 17, the same being disposed in pairs and being oppositely positioned for engagement upon the opposite sides of the rails. The clamps 17 each comprise shanks 18 which are beveled at their upper faces for engagement beneath the plate 10 and adapted for insertion through the slots 16, the inner ends of the shanks 18 being turned upwardly and being provided with lips 19 which engage the opposite sides of the bases of the 15 rails 11 and 12. For the purpose of securing the clamps 17 against the under face of the plate 10 a rest 20 is employed which comprises an elongated metallic bar extending practically the entire length of the plate 20 and being provided at its opposite ends and at its intermediate portion with upwardly extended bolts 21 which are passed through apertures formed in the plate 10 and which are held in such position by the provision of 25 suitable clamping nuts 22. The rest 20 is provided at its opposite extremities with oppositely beveled faces formed in the upper edge thereof as at 23 and 24, the beveled faces 23 and 24 engaging the under edges of 30 the shanks 18 to cause the shanks to impinge against the under face of the plate 10. When thus positioned the inner extremities of the shanks 18 are held in spaced relation to the adjoining edges of the beveled faces 35 23 and 24 in order to admit of the downward movement of the same upon the disposition of weights upon the rails 11 and 12 which are positioned over the same and engaged between the clamps 17. Owing to the 40 formations of the clamps 17 it is readily observed that when the rails 11 and 12 are depressed the plate 10 at the points of support of the rails is depressed and causes the inward movement of the lips 19 against the 45 webs of the rails 11 and 12 and thereby causes the firm gripping action upon the same. The rest 20 limits the movement of the clamps 17 by reason of the formation of the beveled faces 23 and 24 which engage 50 the lower edges of the shanks 18 when a sufficient weight is disposed upon the rails 11 and 12 and thereby prevents the further downward movement of the same. The plate 10 may be provided with any number 55 of slots 16 which are arranged in parallel and which are formed for the purpose of admitting of the positioning of any number of clamps 17 in order to firmly grasp the

rails 11 and 12, such formation adapted particularly where two rails are jointed. It is also observed that the clamps 17 may be spaced owing to the length of the slot 16 in order to admit of the positioning of fish-plates or the like against the opposite sides of the rails 11 and 12 and to be caused to hold the same rigidly in position. The resiliency of the tie may be regulated to a great extent by means of the clamping nuts 22 which regulate the distance between the under face of the plate 10 and the beveled faces 23 and 24.

In the drawings is disclosed a modification of the tie which comprises a metallic plate 25 adapted for engagement upon the upper face of any suitable support and which is provided with pluralities of apertures for the reception of bolts 26 which are carried upon rests 27, the latter being formed of short lengths of metal and having beveled faces 28 and 29 at the upper edges of the same for the reception of clamps 30 of a construction as specified.

In securing the rails 11 and 12 upon the plate 10 the same are positioned over the slot 16 when the clamps 17 are inserted through the apertures and engaged against the opposite sides of the bases of the rails, the rest 20 being spaced downwardly from the plate 10 sufficiently to admit of the insertion of the shanks 18 of the clamps. The rest 20 is now drawn upwardly against the under face of the base 10 and drawn tightly against the same through the medium of the clamping nuts 22 and bolts 21 which causes the shanks 18 to impinge against the under face of the plate 10 and to thereby rigidly hold the clamps 17 in position. Owing to the provision of the beveled faces 23 and 24 the inner ends of the shanks 18 are held upwardly from the beveled faces 23 and 24 and are supported in such position by means of the resiliency of the shanks 18 as the same impinge against the under face of the plate 10 and the outer portions of the inclined faces 23 and 24. When the clamps are thus in position the earth or other bed forming substance is packed around the edges and forced upwardly beneath the flange 13 which securely holds the tie in position. The shanks 18 of the clamps 17 are of such a length as to admit of the withdrawal and insertion of the same when the rests are lowered, which is accomplished by the releasing of the nuts 22 from the upper face of the base 10. It is observed that when a weight is disposed upon the rails 11 and 12 the plate 10 is caused to bend downwardly and to carry therewith the shanks 18 thus throwing the lips 19 more closely against the opposite sides of the bases of the rails 11 and 12 and thus serving to clamp the same more rigidly.

in position. In adjusting the distances between each pair of the clamps 17 it will be noted that the rest 20 is distanced from the plate 10 according to the positions of the 5 respective shanks 18, which adjustment is effected through the medium of the beveled faces 23 and 24.

Having thus described the invention, what is claimed as new is:—

10 A tie as specified comprising a plate having slots longitudinally formed in the opposite ends thereof, said plate adapted to support rails disposed over the slots therein,

clamps positioned in pairs through the slots and engaged against the rails, a rest having 15 beveled upper faces for engagement with the under edges of said clamps, said rest adapted to admit of the downward movement of said clamps upon the disposition of weights upon the rails.

20 In testimony whereof I affix my signature in presence of two witnesses.
